UNITED STATES PATENT OFFICE.

JAMES BARTLETT, OF SOUTH TOTTENHAM, ENGLAND.

ACETYLENE-GAS GENERATOR.

SPECIFICATION forming part of Letters Patent No. 780,968, dated January 31, 1905.

Application filed December 12, 1902. Serial No. 134,954.

To all whom it may concern:

Be it known that I, JAMES BARTLETT, plumber and electrician, a subject of the King of Great Britain and Ireland, residing at 42 5 Broad Lane, South Tottenham, in the county of Middlesex, England, have invented certain new and useful Improvements in Acetylene-Gas Generators, of which the following is a specification.

10 This invention relates to an improved automatic generator for the production of acetylene gas which is worked on the principle of a gasometer for regulating the supply of water and storing the gas. For this purpose I provide a large vessel containing water and fitted with guides for guiding the vertical motions of an inner inverted vessel or drum acting on the principle of a gasometer. This drum stores the gas as it is generated, and by its motion 15 automatically acts upon a valve to regulate the supply of water to the carbid. The said valve is fitted within a water-tank attached to the gasometer and is kept closed by a spring. As the drum descends by the use of the gas 20 it acts upon the valve-spindle so as to open the said valve and admit water from the tank to the carbid-holder, which is placed in a chamber or generator, and in order to clearly understand my invention reference is had to 25 the accompanying sheets of drawings, in which—

Figure 1 is a front elevation, partly in section, of the apparatus. Fig. 2 is a vertical section at right angles to Fig. 1, and Fig. 3 is a 30 partial plan of the same. Fig. 4 is a separate view in section of one of the generators; and Fig. 5 is a section, to an enlarged scale, of the lower end of the valve-spindle and valve for regulating the water-supply. 35 Fig. 6 is a separate view in elevation of a siphon safety-valve.

a is the outer vessel of the gasometer, containing water, and b is the inner drum or cylinder, guided in its vertical movement by the 40 cross-bar c, fixed to the vessel a, and guide-brackets d, carried by drum b.

e is the water-tank, fixed to the front of the vessel a, and f is the valve for feeding water from the said tank to the generators. The 45 spindle g of this valve is tubular, as shown in

Fig. 5, and is provided with perforation h, and its upper end is fitted with a spring i, bearing against a tubular guide j, which is supported by a cross-bar k, fitted to the top of the tank. The guide j is connected to the valve 55 by an outer tube l, and m is a branch pipe leading from the valve to a pipe n and through pipes o o and the vertical perforated pipe p to each separate carbid-holder q through the perforated conical bottom r and perforated 60 tube s of the same. The valve consists of a leather washer t, which closes against the open end of the junction n by the action of the spring i. v is another branch from the spindle g, the object of which is hereinafter explained. 65 w is the arm fixed to the top of the drum b for bearing upon and forcing down the valve-spindle.

x is the chamber within which the carbid-holder is placed, the whole forming a generator 70 fixed to each side of the vessel a. These chambers are formed with double sides, leaving a space all round which is filled with water for keeping the parts cool, and they are each provided with a cover y, fixed by wing-nuts z 75 and made air-tight by bearing upon an india-rubber ring held in a recess, as shown.

The pipe p is fitted with a back-pressure valve p' to prevent any liquid contained in the carbid-holder q passing into other generators. 80

A is a cleaning screw or plug fitted in front of each generator, by removing which water can be poured through the latter when the holder q is removed out into the tank placed 85 beneath for flushing said generator.

B is the purifying box or receptacle, connected to each generator by the pipes C and filled with wadding or other material, and D is the purifying-box at the bottom of vessel a. 90 This box is provided with a perforated plate E, above which is placed coke or pumice-stone and beneath it wadding and rotten-stone.

F is a pipe leading from box D up into the drum b.

G is a screw or cleaning-out plug in the bottom of the box. 95

H is a pipe leading from the purifier B to purifier D and fitted with a cock I, and J is a pipe leading from purifier D to a third puri- 100

fier K, also filled with wadding and rotten-stone and carried in the tank e, the pipe passing through the water in the latter, as shown in Fig. 3, so that it is always kept cool.

5 L is the gas-supply pipe to the burners, fitted with a tap M and a screw-coupling N.

O is the safety-valve, fitted to the top of the drum b.

The operation is as follows: The vessel a is 10 filled with water and the coupling N disconnected. The tap M is then turned on to let out the air, when the coupling is again connected and the tank e filled with water. The spaces surrounding the generators are also 15 filled with water through a screw-plug in the top.

The covers y of the generators are removed and the holders q, filled with carbid, placed in the latter or fresh ones supplied, when the covers are again fixed by the nuts 20 z.

25 One or more of the cocks o' of the pipes o is or are then turned on. The valve f being open, water from the tank e thus passes through the pipes n and o to one or more of the carbid-holders by the pipe p and the gas generated passes through the perforations in 30 the holders and through the pipes C into the first purifier B. It then passes by the cock I into the second purifier D, through the packing in the lower part and coke or pumicing- 35 stone in the upper part thereof, and up the pipe F into the drum b of the gasometer, thus raising said drum and releasing the pressure on the valve-spindle g, so as to enable the spring i to close said valve and stop the passage of the water to the generators. The gas thus ceases to be generated until by its use 40 the drum falls again and opens the supply of water to the generators. The gas stored in the drum b passes down the pipe F back into 45 the purifier D, from whence it escapes by the pipe J, passing through the tank e into the third purifier K and out by the pipe L to the burners. Should the safety-valve o get stuck or not be in proper working order, the gas 50 and water is forced back through the several pipes and chambers to the perforation h in the valve-spindle g, up which they pass to the branch v and from thence escape by a pipe to any desired spot, thus preventing any possibility of explosions.

The gasometer is fitted with legs P or other supports, as desired. I may also employ another safety-valve working on the principle of a siphon-tube, as shown at Q, Figs. 1 and 55 6, which is connected with the upper part of the generator-chamber. The said tube is pro-

vided with or leads into a chamber R and contains water, oil, or other liquid to act as a seal in its lower bend. Should the pressure of gas in the generator overcome the liquid column, the latter is forced into the chamber R, thus permitting the gas to escape by the upper pipe S.

The carbid-holder q is, as before described, placed in the generator-chamber, and when 60 the carbid is used up the said holder is taken out of the chamber and may be thrown away and a new holder filled with carbid substituted therefor.

The safety-valves may all be connected to 70 one common pipe for leading the surplus gas to any desired place.

Having now fully described the nature of my said invention, what I claim, and desire to secure by Letters Patent, is—

1. In an acetylene-gas generator the combination of a gasometer for storing gas, a water-tank connected thereto, a purifier placed in said tank, through which the gas passes on its way to the burners, a valve also placed in 80 the tank and opened by the downward motion of the gasometer-drum, two or more generator-chambers to which water is fed by the said valve, an inner chamber fitted to each of the generator-chambers and consisting of a metal 85 box formed with a conical bottom, a water-supply pipe fitted to the latter, a carbid-holder placed in the inner chamber and formed with a conical perforated bottom, a perforated tube fitted to the latter and surrounding the water-supply pipe, and an air-tight cover fitted to the generator-chamber, substantially as described.

2. In an acetylene-gas generator the combination with a water-tank such as e of a water- 95 feeding valve f, tubular spindle g provided with a perforation h a spring i for closing the same, a second tube l inclosing the spindle g, an arm w acting upon said spindle, a drum or holder b carrying the said arm, gas-generators, to which water is admitted by the valve f, and a branch pipe v fitted to the upper end of the spindle g to serve as a safety-valve for the passage of any extra pressure of gas and water, substantially as described.

In witness whereof I have hereunto set my hand in the presence of two witnesses.

JAMES BARTLETT.
